UNITED STATES PATENT OFFICE.

WILLIAM GILDOW AND MYRON SCHOCK, OF OAK HARBOR, WASHINGTON.

FOLDING UMBRELLA.

1,230,888.

Specification of Letters Patent. Patented June 26, 1917.

Application filed January 9, 1917. Serial No. 141,413.

To all whom it may concern:

Be it known that we, WILLIAM GILDOW and MYRON SCHOCK, citizens of the United States, residing at Oak Harbor, in the county of Island and State of Washington, have invented certain new and useful Improvements in Folding Umbrellas, of which the following is a specification.

The invention has for an object to provide an improvement in the construction and action of folding umbrellas of that kind which fold into a length approximately one-half the length of a rib of the umbrella as ordinarily constructed. Another important purpose particularly is to give a construction of stem and handle which are particularly adapted to use in ladies' umbrellas and parasols, or others, in which a very long handle is employed, providing a construction and arrangement whereby such parts may be folded and collapsed into as small a length as desired without multiplying the number of joints needlessly, nor complicating the manufacture of such an appliance objectionably. Another object is to give a construction which is adapted to permit ready disposal of the ferrule of the umbrella within the folded parts, without requiring the ferrule to be specially manipulated or detached. Another important aim is to give a construction in which the securement of the device either in folded or in extended position will not require the provision of any latches or push buttons projecting from the sides of the handle nor saliently noticeable. A further important object is to give a desirable form of central joint in the stem which will not tend to collapse, but on the contrary will tend to move into extended position under the action of a spring associated therewith. An additional object is to give an improved form of handle joint. Further objects, advantages and features of invention lie in the construction, arrangement and combination of the parts as herinafter described and shown in the drawings, wherein,

Figure 1 is an elevational view of an umbrella frame constructed in accordance with our invention, in extended position,

Fig. 2 is a sectional view of the device in folded position,

Fig. 3 is an enlarged detail of the central stem joint,

Fig. 4 is an enlarged view of the handle joint,

Fig. 5 is an enlarged longitudinal sectional view of the stem from its central joint upwardly, in extended position,

Fig. 6 is a detail of the rib joint, extended,

Fig. 7 is a detail of the sliding sleeve,

Fig. 8 is a detail of the upper stem section,

Fig. 9 is an enlarged detail of the clamping device.

There is illustrated an umbrella frame including the stem body A, and handle B, upon which ribs C of a suitable construction are mounted.

The stem portion includes a lower section 10, and an upper section 11, the upper section being sufficiently large to receive the upper end of the lower section 10 slidably therein a distance. Each is formed of suitable steel tubing, such as is customarily employed for such purposes. The section 10 is a plain cylindrical tube slotted on opposite sides at its upper part and having a hinge link 12 pivoted therein for movement into the slot to a position at right angles to the stem. The opposite end of this link is connected to a tube 13 of the same diameter as the lower stem portion 10, slidable in the upper section 11, and connected at its outer end to a ferrule member 14, also slidable in the upper section 11 of the stem. Confined in the outer part of the tube 13 there is a helical spring 15, secured at its inner end to a pin 16 fixed through the upper section 11 of the stem, the tube 13 having slots on opposite sides permitting it to slide inwardly with relation to the pin 16. The spring is thus active to force the ferrule 14, tube 13 and stem section 10 toward the outer limit of their movement with relation to the upper section 11, this outward movement being limited by the pin 16 engaging the inner end of the slot in the tube 13. When at the outer position the hinge link 12 is drawn

upwardly into the upper section 11 and the section 10 of the stem also projects into the upper section a short distance. The upper section is exteriorly threaded at its inner 5 end, and has engaged thereon an internally threaded sleeve 17 reduced in diameter at its inner or lower part to fit snugly around the lower section 10 of the stem, having a tapered inner surface adapted to com- 10 press a split ring 18 located loosely within the sleeve next to the end of the upper section 11. The threaded end of the upper section may be also formed with a conical female seat, and the ring 18 is formed with beveled edges on both the upper and lower 15 sides, to facilitate its compression when the sleeve 17 is screwed into place. By this means the ring may be compressed forcibly against the section 10, holding it firmly 20 against sliding movement, but when released the stem section 10 may be drawn downwardly clearing the hinge link 12 from the upper section and permitting it to be folded as shown in Fig. 2. In order that 25 when in folded position the action of the spring 13 will not tend to draw the device into extended position, the pivoted end of the link next the upper section of the stem is arranged to extend across the end of the 30 stem and rest on opposite sides of the sleeve 17, as illustrated.

The upper end of the upper stem section is provided with the usual crown piece 19, to which upper rib sections 20 of the usual U- 35 shape in cross section are connected in the customary manner. Bracing ribs 21 are connected to the outer ends of these upper rib sections 20, and at their inner ends are connected to a crown piece 22 carried by a 40 sliding sleeve 23 of a suitable length to rest against the sleeve 17 when the umbrella is extended in normal position and hoisted, so that the brace and rib extend at approximately the same angle from the stem. A 45 suitable slight enlargement 24 may be formed on the lower end of the sliding sleeve if desired, although this is not considered essential, and is done principally to give an attractive appearance to the appli- 50 ance, and indicate that the sleeve 23 is to be manipulated. Pivotal connection to the upper rib section 20 there is an outer rib section 25, the outer part of which may be the same as that of the ordinary umbrella rib. The pivotal connection is made by means of a link 26 of suitable material connected pivotally to the adjacent ends of the rib sections 20 and 25, the central portion of the rib section ends are cut away to form 55 ears pivoted on the link in a suitable manner, so that the outer rib section may be folded outwardly and backwardly upon the inner section, and the link is suitably extended beneath the rib sections to support them

firmly in extended position and prevent 65 breaking of the joints downwardly.

The lower end of the stem section 10 is crimped or turned inwardly to engage snugly around the stem portion of a telescoping link 27, located in the handle B. 70 This link is formed with a head 28 at its upper end fitting snugly and slidably in the lower stem section 10, and adapted to engage against the inturned portion of the stem section when drawn downwardly. The handle 75 B is formed with an ornamental body portion 29, having the cylindrical passage 30 therethrough opening on its upper end, and in the present instance the handle may be considered as formed of wood. In this 80 event a bushing sleeve 31 is fixed in the upper end of the handle, of suitable size to receive the lower stem section 10 snugly and slidably, and the telescoping link 27 is provided with a head 32 fitting snugly in the 85 passage 30 and adapted to engage against the lower end of the bushing 31 when drawn outwardly to fullest extent. The link is of such length that it will be checked by the lower end of the bushing 31 when the lower 90 end of the stem section 10 is still engaged a sufficient distance within the bushing to form a rigid connection. The bushing 31 is exteriorly threaded at its outer end, projecting a slight distance beyond the wood portion 29 of the handle, and receives thereon a clamping sleeve 17', similar to the one 17 before described, except slightly larger, which operates to compress a split clamping ring 18' similar to the one 18 before mentioned, 100 whereby the lower stem section may be securely locked in extended position or closed position, as desired.

It is important to notice that the link 26 in the showing of the umbrella rib is formed 105 with a small intermediate transverse aperture 33 so that when a cover is secured upon the frame it may be attached to the link and the proper folding of the cover at the same time with the frame thereby assured. 110

In use, in order to fold the device, when it is extended, it is simply necessary to unscrew the clamp sleeves 17 and 17' a short distance, grasping the sliding sleeve 23 in one hand and drawing outwardly upon the 115 handle of the umbrella with the other, while the ferrule is pointed downwardly in order to cause the outer parts of the ribs and cover to fold properly. This will move the sleeve toward the ferrule, and after the rib 120 braces have passed a position at right angles to the stem will cause the braces to draw the rib joints inwardly toward the stem. The inward movement of the ribs will then interfere with the insertion of the hand further therebetween, and the remainder of the movement may be accomplished by grasping the ribs and bearing them all inwardly to- 125

ward the stem. The outer rib sections are caused to fall downwardly by gravity, folding the outer part of the cover neatly against the inner part, as will be understood. After the folding movement of the ribs has begun, or after it has been completed, if desired, the stem section 11 or the folded ribs may be firmly grasped and the handle or lower stem portion drawn outwardly with such force as to compress the spring 15, drawing the ferrule inwardly until its outer end lies even with the outer end of the ribs when folded and the hinged link 12 is moved clear of the upper stem section and may be folded into crosswise position. The handle B is then forced inwardly on the stem section 10 until it strikes against the hinge link, which may also be extended beyond the pivot adjacent its lower stem section so as to engage across both sides of the handle when thus positioned, and by tightening the clamp sleeve 17' unfolding of the handle portion with respect to the hinged link will be prevented.

It will be seen that a very compact folding umbrella with elements of extreme simplicity is provided, the use of which is attended with a minimum of difficulty and complications, and the manufacture of which may be accomplished at an extremely low cost.

It should be noted that the links 26 in the ribs are of a sufficient length to cause the inner and outer rib sections to lie in spaced relation when folded, giving ample room for the accommodation of the cover therebetween when folded without liability of pinching thereof with consequent damage. The intermediate portions of the rib ends are cut away so as to strike against the link when folded into parallel relation, thereby checking further folding movement and preventing chafing of the fabric of the cover between the rib sections.

What is claimed is:

1. In an umbrella of the character described, a stem construction including an upper tubular stem element, a ferrule longitudinally slidable therein and adapted to project from the outer end, a second member slidable in the stem section, a spring support carried by said stem section, a spring confined between said support and said ferrule said second named member connected to said ferrule, under tension to project the ferrule to the outer limit of its movement, a hinge link connected to the inner end of said second named member positioned to lie within said stem sections when the ferrule is at the outer limit of its movement, a lower stem section connected to the hinged link, and extending a distance within the upper stem section when the ferrule is at the outer limit of its movement, and a handle section adapted to be disposed in parallel relation with the lower stem section at 65 times.

2. In an umbrella, a stem section, a ferrule element slidable therein and adapted to project therefrom, a sliding tube in the ferrule section connected to the ferrule, a hinge link connected to the opposite end of the tube, a lower stem section connected to the link, said connections and link being disposed and arranged to lie within the said stem section when the ferrule is normally projected, said tube having a longitudinal slot therein, a pin fixed in the stem section and extending through the slot, and a spring confined between the pin and the ferrule, under tension to project the ferrule to its outermost position.

3. In an umbrella, two stem sections, a sliding element in one, resilient means tending to move the sliding element thereinto, a hinge link connected between said sliding element and the other stem section, said link being extended at each end to project over opposite sides of the respective stem sections, and a telescoping handle element adapted to be moved on said other stem section into close abutting engagement with said link, and means to secure the telescoping element in adjusted position.

4. In an umbrella, a tubular stem section, a sliding element therein, resilient means engaged with the sliding element and stem section tending to draw the sliding element into the stem section, a hinge link pivoted on said sliding element having projecting end portions adapted to extend across both sides of the stem sections when drawn outwardly and disposed at right angles thereto, for the purposes described, and a second section connected to the link having a portion to engage in said stem element.

5. An umbrella of the character described comprising stem elements including an upper section, a crown at the outer end of the upper stem section, inner rib sections pivotally connected to the crown, a sliding sleeve on said stem section, a crown on the sliding sleeve, braces pivoted on the crown last mentioned and connected at their outer ends to the outer ends of said upper rib section, means to limit downward movement of the sleeve at a position with the braces in normal supporting relation to the upper rib sections, the sleeve being slidable into position with its crown in close relation to the first named crown, said braces being of a length to lie in close parallel relation with the upper rib sections when at the inner limit of their movement, and outer rib sections pivotally connected to the first named section respectively and foldable outwardly and upwardly into close relation therewith.

6. In an umbrella of the character described a tubular stem section, a headed link

slidable in the lower end thereof, inwardly projecting portions on the stem section to engage under the head of the headed link, a handle element having an enlarged passage, said link having an enlarged head to fit snugly in the passage, said handle element having a bushing element therein engaged snugly around the stem element and extending inwardly a distance to engage the head of the link to limit its outward movement and the outward movement of the stem

section as described, and means to secure the handle element and stem section against relative sliding movement.

In testimony whereof we have affixed our 15 signatures in presence of two witnesses.

WILLIAM GILDOW.
MYRON SCHOCK.
